UNITED STATES PATENT OFFICE.

LEWIS C. VAN RIPEE, OF CHICAGO, ILLINOIS, ASSIGNOR TO BRIGHT ENVELOPE COMPANY, OF CHICAGO, ILLINOIS, A CORPORATION OF SOUTH DAKOTA.

ENVELOP.

1,127,702.

Specification of Letters Patent. Patented Feb. 9, 1915.

Application filed August 2, 1911. Serial No. 641,974.

To all whom it may concern:

Be it known that I, LEWIS C. VAN RIPEE, a citizen of the United States, residing at the city of Chicago, in the county of Cook and State of Illinois, have invented certain new and useful Improvements in Envelops, of which the following is a full, clear, and exact description, reference being had to the accompanying drawing, forming part of this specification.

My present invention has relation more particularly to that class of envelopes designed for the carrying through the mails of printed matter such as catalogues, circulars, price lists, or the like. An example of this type of envelop is illustrated in Letters Patent No. 941,392, granted to me November 30, 1909, and in Letters Patent No. 958,785, granted to the Bright Manufacturing Company, as my assignee, May 24, 1910. In this class of envelopes, the construction must be such as to securely retain the printed matter during its transmission through the mails and yet permit the envelop to be opened for the purpose of inspection.

The object of the present invention is primarily to provide a more secure interlock for the inspection flap of the envelop, i. e., the flap which is to be withdrawn to permit inspection by the postal authorities of the contents of the envelop. The envelop is hereinafter described, illustrated in the accompanying drawing and particularly pointed out in the claims at the end of this specification.

Figure 1 is a plan view of my envelop in unfolded position. Fig. 2 is a view with the parts partially folded. Fig. 3 is a view of the envelop complete. Fig. 4 is a view in vertical cross-section through the envelop on line 4-4 of Fig. 3, this section being shown upon an enlarged scale.

My improved envelop is shown as comprising a front portion 1, side flaps 2 and 3, a sealing flap 4 and an inspection flap 5. The side flaps 2 and 3, when folded over upon the inner face of the front 1, constitute the back portion of the envelop. Preferably, the side flaps are formed with supplemental flaps 2^a and 3^a which, when folded over upon the flaps 2 and 3, serve to reinforce and strengthen the edges of the flaps.

In the present construction, as in the construction set forth in the before mentioned

Letters Patent, a supplemental strip 6 extends across the interior of the body of the envelop adjacent the inspection flap 5 and this strip cooperates with the flaps 2 and 3 in forming a pocket to receive the unsealed inspection flap 5 of the envelop. In the construction of envelop shown in the above mentioned patents, the retention of the printed matter within the envelop was effected by merely tucking the inspection flap 5 within the pocket formed between the side flaps 2 and 3 and the supplemental strip 6. The main purpose of the present invention is to provide means for detachably interlocking the inspection flap within the pocket after it has been inserted therein.

In the preferred form of the invention illustrated in the drawing, the inspection flap 5 has one of its ends cut away and provided with a tongue 5^a. The end of the inspection flap 5 is narrowed or cut upon a taper along the line 5^b, so that when the flap 5^a is turned to closed position, the edge of the flap will not be exposed. The face of the supplemental strip 6 is shown as provided with gum or like adhesive material at 6^a, and, preferably, this adhesive material is extended along a curved line 6^b to approximately the inner edge of the strip 6.

In forming the envelop, the supplemental flaps 2^a and 3^a will first be folded on to the flaps 2 and 3, respectively, and then these flaps 2 and 3 will be folded over on to the supplemental strip 6, as indicated in Fig. 3 of the drawing. Preferably, the supplemental strip 6 has a line of adhesive material 6^c extending over its inner edge and, if desired, also extending as at 6^d partially along its side edges; and, when the flaps 2 and 3 are turned over on to the supplemental strip 6, they will be securely connected to the supplemental strip by the adhesive material upon the face thereof. The edge of one of the flaps, as for example, the flap 3, will be provided with adhesive material, 100 to unite this flap 2 to the flap 3 when the flaps are in folded position.

From the foregoing description it will be seen, reference being had particularly to Fig. 4 of the drawing, that when the flaps have been folded on to the supplemental strip and have been sealed thereto, as above described, a pocket will be formed between the supplemental strip 6 and the flaps 2 and 3 to receive the inspection flap 5 and this in-

spection flap may be readily inserted within such pocket, as clearly shown in Fig. 4 of the drawings. When the inspection flap is inserted within the pocket, the tongue 5^a of this flap will enter behind the gummed point 6^a at which the supplemental strip 6 adheres to the flap 2, and the tongue in such position will form an interlock which will effectively serve to prevent the accidental withdrawal 10 of the inspection flap from the pocket. It will be readily understood, however, that the postal inspector can easily withdraw the inspection flap when it is desired to view the contents of the envelop. In withdrawing 15 the inspection flap, it should be moved initially in the direction of the arrow shown by Fig. 3 of the drawing, until the tongue 5^a is out of the pocket formed by the gummed point 6^a, after which the flap can 20 be drawn straight outward in the usual way. Any tendency of the contents of the envelop to force open the flap will be exerted at right angles to the length of the inspection flap 6, and, consequently, will be resisted by the 25 interlocking tongue 5^a of the flap.

Inasmuch as the supplemental strip 6 is gummed to the back portion of the envelop, as at 6^a, the pocket between the supplemental strip and the inspection flap is thus formed 30 with a contracted mouth which serves to resist the accidental withdrawal of the laterally projecting tongue 5^a of the inspection flap when such tongue has been placed within the pocket.

35 It is obvious that the precise details above set forth may be varied without departing from the spirit of the invention.

Having thus described my invention, what I claim as new, and desire to secure by Letters Patent, is:—

40 1. An envelop comprising a front portion having integral, opposite side flaps overlapped and united, and having also an integral top closure flap and an integral bottom inspection flap, said bottom inspection flap having one of its lateral side edges cut

away to form a laterally projecting tongue at its inner end, and a separate interior strip united to said side flaps at portions extending along both of the opposite side edges of 50 said inspection flap to thereby form a pocket with a contracted mouth for receiving said inspection flap with the inner end and tongue of the latter extending through and interlocked with the contracted mouth of the 55 pocket, substantially as described.

2. An envelop comprising a front, having an integral top closure flap, an integral bottom inspection flap and opposite side flaps overlapped and united, said bottom inspection flap having inclined side edges one of which is cut away to form a laterally projecting tongue at its inner end and a separate interior strip united to said side flaps along portions extending about the end and both 60 of the opposite side edges of said inspection flap, and about said tongue to thereby form a pocket with a contracted mouth for receiving said inspection flap with its inner end and tongue extending through, and interlocked with the contracted mouth portion of the pocket, substantially as described. 70

3. An envelop comprising a front portion having integral opposite side flaps overlapped and united, and having also an integral top closure flap and an integral bottom inspection flap, said bottom inspection flap having one of its lateral side edges cut away to form a laterally projecting tongue adjacent its inner edge and a separate interior 80 strip united to said side flaps along its inner edge and around the side edges of said inspection flap and extending beneath and forming a guide for said inspection flap, and also forming a pocket together with said 85 side flap whereby said inspection flap is locked when in closed position.

LEWIS C. VAN RIPER.
